Primary Examiner — Patricia Palasik(74) *Attorney, Agent, or Firm* — Hahn Loeser & Parks, LLP;
Keith J. Marcinowski(57) **CLAIM**

The ornamental design for a control knob, as shown and described.

DESCRIPTION

FIG. 1 is a perspective view of a control knob for a wire feeder;

FIG. 2 is a front perspective view of the control knob of FIG. 1;

FIG. 3 is a rear perspective view of the control knob of FIG. 1;

FIG. 4 is a bottom perspective view of the control knob of FIG. 1;

FIG. 5 is a top plan view of control knob of FIG. 1;

FIG. 6 is a front elevational view of the control knob of FIG. 1; and,

FIG. 7 is a rear elevational view of the control knob of FIG. 1. The broken lines shown in the figures are for illustrative purposes only and form no part of the claimed invention.
